UNITED STATES PATENT OFFICE.

THOMAS DENTON MILLER, OF CATONSVILLE, MARYLAND.

SHINGLE.

1,226,564.

Specification of Letters Patent. Patented May 15, 1917.

Application filed November 18, 1915. Serial No. 62,111.

To all whom it may concern:

Be it known that I, THOMAS DENTON MILLER, a citizen of the United States, residing at Catonsville, in the county of Baltimore and State of Maryland, have invented certain new and useful Improvements in Shingles, of which the following is a specification.

This invention relates to roofs, and more particularly to an improved tile or shingle so formed as to interlock with similar shingles and also to expose more area to the weather than the ordinary shingle without danger of leakage.

Specifically, the present invention may be regarded as an improvement upon the shingle shown in my Patent No. 1,059,682, dated April 22, 1913, and its objects are to decrease still further the relative overlapping area of the shingles, and thus increase the relative area exposed to the weather, and at the same time produce a shingle which when applied to a roof will produce a neat, ornamental appearance.

In order that the invention may be readily understood, reference is had to the accompanying drawing, forming a part of this specification, and in which,

Figure 1 is a face view of one of my improved shingles;

Fig. 2 is a longitudinal section through the same;

Fig. 3 is an end view thereof on an enlarged scale;

Fig. 4 shows the appearance of the shingles when assembled to form a roof;

Fig. 5 is a longitudinal section substantially on the line 5—5 of Fig. 4, looking in the direction of the arrow;

Fig. 6 is a transverse section substantially on the line 6—6 of Fig. 4, looking in the direction of the arrow; and,

Fig. 7 is a central longitudinal section showing a slightly different form of shingle.

The improved tile or shingle forming the subject of the present invention may be made of any desired material, and is preferably rectangular in shape, as shown in

Fig. 1. The shingle consists of a relatively wide, flat, central portion 1, a pair of longitudinal ribs or beads 2, disposed one on each side of the central portion 1, and a pair of relatively narrow flanges 3, lying between the ribs 2 and the longitudinal side edges

of the shingle. The shingle is provided with a pair of transversely extending ridges 4, which divide the surface of the shingle into three portions *a*, *b*, and *c*. The portions *a* and *b* together constitute the exposed area 60 of the shingle and are preferably relatively wide and of similar shape and size. The portion *c* constitutes the covered or overlapped area of the shingle and is of relatively narrow width. In laying, the portion 65 *c* is, of course, at the upper end of the shingle.

By reference to Fig. 2, it will be seen that the three portions *a*, *b*, and *c*, formed by the ridges 4, lie in different but substantially 70 parallel planes. The lower edge of the lowermost portion *a* is preferably bent downwardly, as indicated at 5. This downwardly bent edge is adapted to engage the upper ridge 4 of the shingle immediately 75 below it, as shown in Fig. 5, thus overlapping the upper portion *c* of said lower shingle. The shingles are secured in position on the roof by means of nails which are driven at the points indicated by the 80 reference character 6, such points being located just above the lower ridge 4, on each side of the shingle in the flanges 3. It will be seen that when the shingles are laid as below described, the nail heads located at such 85 points will be entirely covered.

Referring to Fig. 4, it will be seen that the shingles are laid in horizontal rows as usual. The present arrangement, however, differs from that usually employed in that the shingles of each row are spaced relatively far apart. In the drawing A and C represent two shingles in the same horizontal row, and it will be seen that these are separated by a distance almost equal to the width of 95 the central portion of the intermediate shingle B of the row immediately below. Shingles D and F of the row above are in the same way separated a distance almost equal to the width of the shingle A, etc. It will 100 also be seen that the portions *a* and *b* of each shingle are exposed to the weather, only the portion *c* being covered or overlapped by the shingle immediately above. By virtue of the arrangement above described, it will 105 be observed that the relative proportion of each shingle which is exposed to the weather is much greater than in the case of ordinary shingles, and is also greater than in the case of the shingles covered by my patent above 110

referred to. It will also be noted that the ribs 2 of each shingle overlap the upper portions of the ribs of the two adjacent shingles in the next lower row, so that the lower portion of each shingle has all three of its edges exposed to the weather. Owing, however, to the efficient seal formed by the ribs and turned-down edge 5, leakage is prevented.

As will be seen by reference to Fig. 4, the lower edges 5 of the shingles of any one row are in alinement with the ridges 4 of the intervening shingles of the next lower row. The result of this is that, at a little distance, the appearance of a continuous line separating the rows of shingles is produced, thus simulating the effect of the usual method of laying shingles.

In some cases where the shingle is made of sheet metal, it may be desirable to form the same slightly concave or bow-shaped, as shown in Fig. 7. By reference to this figure, it will be obvious that the central portion 1' of the shingle is not strictly flat, but is somewhat curved and that the surfaces a' , b' , c' lie in different, although not strictly parallel planes. When a shingle of the form shown in Fig. 7 is nailed to a roof, the lower edge 5 is thus forced into very close contact with the shingle below it.

30 What I claim is:

1. A roof consisting of a series of horizontal rows of overlapping shingles, each shingle having a relatively wide, flat, central portion, and a pair of straight longitudinal ribs arranged one on each side and extending throughout the length thereof, the ribs of each shingle of an upper row overlapping those of two adjacent shingles of the next lower row, and each shingle of a lower row having one transverse ridge across the said central portion against which ridge the lower end of the shingle in the upper row second above it engages, and another transverse ridge in alinement with the lower

edges of the two overlapping shingles of the 45 next upper row immediately above it.

2. A roof consisting of a series of horizontal rows of overlapping shingles, the shingles of each row being spaced relatively far apart, and each shingle overlapping the 50 sides of two adjacent shingles of the next lower row, and the upper end of the shingle immediately below it, each shingle having a transverse ridge and the lower edges of the shingles in one row being alined with the 55 ridges of the shingles in the next lower row, whereby the appearance of continuous horizontal lines between the rows of shingles is produced.

3. A roof consisting of a series of horizontal rows of overlapping shingles, each shingle having a pair of longitudinal ribs extending throughout the length thereof, and arranged one on each side, said ribs being spaced from the side edges of the shingle to 60 form lateral nailing flanges, each shingle of an upper row partially overlapping the said ribs and flanges of two adjacent shingles of the next lower row, and each shingle having two spaced transverse ridges extending 65 across the same, the shingles being laid so that the lowermost ridge of each shingle in one row is in substantial alinement with the lower edges of the two overlapping shingles of the next upper row, each of said shingles being secured by two nails driven through 70 said flanges at points between said ridges, said nails also passing through the two adjacent shingles of the next lower row above the upper transverse ridge of such shingles, 75 whereby every nail head is covered by an overlapping shingle, and a transverse ridge extends between the two nails passing through each side of every shingle.

In testimony whereof I have affixed my 85 signature.

THOMAS DENTON MILLER.
